UNITED STATES PATENT OFFICE

2,448,992

PROPELLING POWER UNIT FOR INVALID
WHEEL CHAIRSHomer Love, Cecil E. Brittain, Bowen D. Langton,
and Ralph E. Van Gundy, Wichita, and Charlie
E. Van Gundy, Valley Center, Kans.

Application June 16, 1947, Serial No. 754,970

1 Claim. (Cl. 180—23)

1

This invention relates to a propelling power unit for an invalid wheel chair, and has for its principal object the provision of propelling and guiding power means for a conventional wheel chair.

Another object of this invention is to arrange electric switch and steering controls accessible to the invalid of a wheel chair, whereby the chair may be power propelled by the invalid's own manipulation of the controls.

A still further object is to provide a propelling power unit having one power actuated wheel, whereby the same may be turned on its vertical diametrical axis for affecting the guiding or directional movement of the chair.

A still further object is to drive the power wheel by a reversible motor having storage batteries to energize the motor.

A still further object is to rockably attach the power unit rearwardly of the wheel chair in such a way so that the chair is not altered or affected, other than being conveyed by the power unit, in which case, should the power unit be temporarily detached, the chair may be operated in the usual manual manner.

A still further object is to provide a one wheel power actuated unit that has a compartment for storage batteries and having rockable struts to normally retain the unit upright when disconnected from the chair.

A still further object is to provide two bearings for coupling the power unit to the chair's frame to retain the power wheel vertically when in its action of propelling and guiding the chair, and furthermore the coupling being rockably mounted will provide vertical rock of the power wheel and the wheel chair, separately, or simultaneously, whereby traveling over irregular surfaces is possible without affecting either power unit or the wheel chair.

A still further object is to choose a conventional motor for actuation of the power unit that may be reversed for a backward motion of the chair, and furthermore said motor being of a type that has embodied therein an automatic brake to stop rotation of the motor when de-energized, whereby action is imparted on the power wheel to retain the same against rotation, which in turn serves as a brake for the wheel chair.

A still further object is to arrange the electric switch control for the motor adjacent the wheel chair's arm rest so that the power may be controlled by a momentary touch of the invalid's fingers for affecting a backward movement and a low or high speed forward, selectively; and fur-

thermore a steering wheel likewise being conveniently placed to the invalid for turning the power wheel on its vertical diametrical axis to guide the wheel chair, it being understood that the chair has its usual trailing caster wheels to permit turning of the wheel chair.

5 A still further object is to provide a noiseless power unit for the purpose above stated and having sufficient stored-up energy to provide an appreciable amount of traveling; however, while at rest the storage batteries may be charged by a suitable battery charging equipment, which may be supplied by the manufacturer of this invention.

15 A still further object is to construct a power unit for a wheel chair that is inexpensive to manufacture, efficient in its performance, and easily and readily operated by an invalid in the chair.

These and other objects will hereinafter be 20 more fully explained, reference being had to the accompanying drawings forming a part of this specification, and in which like characters will apply to like parts in the different views.

25 Referring to the drawings:

Fig. 1 is a side elevation, illustrating our invention coupled rearwardly of a conventional wheel chair.

Fig. 2 is an enlarged sectional view of the power unit taken on line 2—2 in Fig. 3.

30 Fig. 3 is a top view of the power unit, the housing lid being partially shown, and the wheel chair's frame being fragmentarily illustrated.

Fig. 4 is an enlarged horizontal section through the power unit housing, and other parts broken 35 away for convenience of illustration.

Fig. 5 is a vertical sectional view of the steering arm, parts being broken away for convenience of illustration.

Fig. 6 is a sectional view of the power unit 40 taken on line 6—6 in Fig. 4.

Fig. 7 is a preferred wiring diagram for electrically controlling the power unit of our invention.

The invention herein disclosed consists of a 45 power unit to propel and guide a conventional wheel chair 8 by coupling the power unit to the chair's frame 9 rearwardly thereof, said chair having its usual caster wheels 10 for supporting the rear end of the chair and permit turning thereof.

It will be understood that no claim is made to the wheel chair's frame and its caster wheels 10, except in combination with our invention for affecting an operative device.

55 The power unit of our invention comprises a

housing having straight vertically positioned side and front walls 11 and 12, respectively, and a semi-circular rear wall 13. Said housing has a lid 14 suitably hinged, as at A, to close the same at its upper extremity, and a bottom 15 to partially close the housing adjacent its lower extremity. The bottom is secured to the sides and front wall a short distance upwardly from the lower extremity of said housing, and has a vertical wall 16 connecting the edge of the bottom, opposite the front wall and the sides of the housing. By the arrangement of the vertical wall and bottom, a compartment is provided for a pair of storage batteries 17 as shown in Figs. 2 and 4.

Secured to the vertical wall 16 and extending rearwardly is a pair of arms B to which is integrally joined a sleeve 18, said sleeve being vertically positioned to serve as a fixed component of a hinge. The rockable component of the hinge consists of a vertical portion 19 having upper and lower horizontal ears 20 to receive therebetween the sleeve 18, said ears being rockably connected to the sleeve by a shaft 21 extending through the ears and sleeve and having pins 22 to lock the shaft with the ears for turning the same. Integrally joined to the sleeve and extending downwardly therefrom is a rod 23, or the like, the lower end of which is joined to a right angle frame 24. Within the frame 24 is mounted a reversible motor 25 having connected thereto a gear case 26 for actuation of a power drive wheel 27, which is rotated and carried by the gear case, as at 28, and suitably retained against longitudinal movement.

It will be understood that the gear case and motor are of standard construction already being manufactured and are rigidly secured in the frame by bolts 29 as shown in the drawings.

The arrangement of the rockable hinge as above described provides an offset so that the power wheel may be positioned centrally between the sides of the unit housing, and also places the vertical diametrical axis of the wheel in axial alignment with the shaft 21 to be turned thereby, as later described, in which case, side tipping tendency of the power unit during turning is eliminated.

The motor 25 may be actuated to rotate the power wheel for moving the wheel chair two speeds forward and one speed backward, and the motor has embodied within its construction a conventional, automatic brake to stop rotation of all parts when current is disconnected to the motor in which case, said motor as arranged will serve as a brake for the wheel chair.

The guiding means for the wheel chair is as follows:

Rigidly secured to the upper end of the shaft 21 is a sprocket wheel 30 over which engages a chain C. The ends of the chain are adjustably secured to the corresponding ends of a pair of cables 31 and 32, said cables extending through an opening in the housing and engaging with their respective pulleys 33 and 34 that are rotatably mounted on a bolt 35 that extends through the lower end of a steering wheel arm comprising a tube 36. Said arm is hollow and rectangular in cross section to provide sufficient working space for the pulleys and cables, as well as to receive an electric conductor 37 therethrough as later described. The cables 31 and 32 extend forwardly in the arm to connect to their respective ends of a chain 38 that engages on a sprocket wheel 39 as shown in Figs. 4 and 5. Cable 31 is provided with a pulley 40 mounted on a bolt 41.

adjacent the pulleys 33 and 34, said pulley 40 serving to direct the cable 31 to its respective inner side of the arm. To actuate the cables and chains, it will be seen that sprocket wheel 39 is rotatably carried at the forward end of the arm by any suitable bearing 42, in which shaft 43 is journaled for rigidly connecting the sprocket wheel to a steering wheel 44 as shown in Fig. 1, the forward end of the arm terminating a short distance forward from the wheel chair arm rest 45 so that the steering wheel may be conveniently reached by an invalid in the chair. By turning the steering wheel, the power wheel is turned on a vertical line taken through the diametrical axis of the wheel, which in turn propels the chair in a desired direction, the turn being controlled by stops 46 secured to the sleeve 18 as shown in Figs. 2 and 6; and as shown in Fig. 3, a sector portion of the steering wheel being removed at its outer side with respect to the chair to permit passage of the chair and power unit through an average sized door opening.

The cables and chains as connected in Fig. 4 will require a clockwise turn of the steering wheel to affect a left hand turn of the chair, however by reversing the connections of the cables at one of their corresponding ends will affect a right hand turn of the wheel chair as the steering wheel is rotated clockwise by the invalid.

The forward end of the arm is closed by a plate 46 as shown in Figs. 4 and 5. The steering wheel arm is adjustably secured to a side of the housing accommodating the invalid by the provision of a pair of angle brackets 48 and 49 as shown in Figs. 1 and 4. Bracket 49 is inwardly positioned from the lower end of the arm and has an elongated slot 50 in its horizontal leg to permit inward and outward movement of the arm at its forward end as adjusting means for the steering wheel, while the housing has an arcuate slot 51 to permit a vertical rock of the arm, whereby the steering wheel may be suitably positioned with respect to height and distance from the wheel chair.

In Figs. 4 and 7 is illustrated the manner of controlling the motor for action of the power wheel. Suitable electric wiring 37 is employed to connect the batteries, the motor, a relay 52, and switches 53 and 54 for their respective function. The electric switches are mounted adjacent the steering wheel so that the same are easily approachable by the invalid in the chair. The switch 54 is a momentary switch to actuate the relay for closing a selected circuit as controlled by the switch 53. The momentary switch 54 is secured inwardly of the arm to be closed by a stem 55 engaging therewith, said stem having on its upper end as shown in Fig. 5 a disc 56 which is pressed to close the relay 52.

Referring to the wiring diagram as illustrated in Fig. 7, it will be understood that by directing a current through point R, the upper battery will be connected to the motor for a backward motion of the chair at a slow speed as only one battery is employed in this circuit. By running a current through point L a slow speed forward will be provided as only one battery is connected, however by closing a circuit through point H an increased speed forward will be the result as both batteries are connected into the circuit. The slow speed is suitable for movement of the chair in congested places and the high speed when plenty of room is available. The switch 53 is any conventional make, wherein the same provides

for three independent circuits for producing a reverse, and a low and high speed forward.

As shown in Figs. 2 and 4, the power unit housing is rockably coupled to the frame of the wheel chair rearwardly thereof by a pair of spaced bearings. Each bearing comprises an upper leaf 57 rigidly secured to the front wall of the housing, and a lower leaf 58 rockably connected to first said leaf as at 59 to retain the frame between the upper and lower leafs of the bearings, as the same are provided with arcuate portions to coincide to the circumference of the frame with respect to cross section but having sufficient clearance to permit rockability of the bearings on the frame. The two bearings are for the purpose of retaining the power unit against side rock and to definitely control the chair in a desired path of movement while the rocking feature of the bearings likewise permit independent rock of the chair and power unit when traveling over irregular ground surfaces.

In some instances, the power unit may be temporarily stored, in which case, the same may be easily detached from the chair by loosening wing nuts 60 which permits separation of the leafs of the bearings and allowing removal of the frame therefrom. When the power unit is stored, a pair of the struts 61 are rocked downwardly to retain the forward end of the power unit in its normal position, each strut having one end rockably secured to its respective side of the housing by a bolt D, while its other end has a rubber sleeve 62 to function as a foot when the strut is engaged.

It will be understood that suitable battery charging equipment will be provided with the invention so that the storage batteries may be charged when the chair is at rest, said charging equipment not being shown in the drawings.

While the present embodiment as shown in the drawings is of a preferred construction of the invention, we desire to emphasize that various changes in construction, proportion and location of the components of this invention may be resorted to as is commonly practiced by manufacturers during the process of improvement, and other modifications may be made as lie within the scope of the appended claim.

Having fully described our invention what we believe is new and desire to secure by Letters Patent is:

5 In a propelling power unit for a wheel chair comprising one wheel and housing for the same, means to connect the housing rockably to a conventional wheel chair without disconnecting any parts of the wheel chair, a motor and gear means to drive the wheel, hinge means to rockably attach the wheel to the housing centrally thereof, a sprocket wheel mounted on the rockable portion of the hinge means to turn the wheel on its diametrical axis to guide the wheel chair, an arm adjustable secured to the housing and extending 10 forwardly to terminate adjacent the side of the wheel chair, a sprocket wheel rotatably mounted in the forward end of the arm, a steering wheel to affect rotation of last said sprocket wheel, chains engaging over their respective sprocket 15 wheels, cables to connect the chains with each other for imparting rotation of the steering wheel to the hinge means, switches mounted on the forward end of the arm and electric wiring to connect the batteries and motor for reversed and 20 forward motion of the chair, and struts for the housing to retain the housing upright when disconnected from the wheel chair.
